US00D653106S

(12) **United States Design Patent** (10) **Patent No.:** **US D653,106 S**
Cohen et al. (45) **Date of Patent:** **** Jan. 31, 2012**

(54) **CONTAINER SHROUD**

(75) Inventors: **Erica Eden Cohen**, New York, NY (US); **Nathaniel Giraitis**, New York, NY (US); **Jonathan Mandell**, Gurnee, IL (US); **Nicolas Oxley**, New York, NY (US); **Jacob Palmborg**, Brooklyn, NY (US); **Jessi Pervola**, Brooklyn, NY (US); **Richard Whitehall**, New York, NY (US)

(73) Assignee: **S.C. Johnson & Son, Inc.**, Racine, WI (US)

(**) Term: **14 Years**

(21) Appl. No.: **29/379,393**

(22) Filed: **Nov. 18, 2010**

(51) LOC (9) Cl. **09-01**

(52) U.S. Cl. **D9/434; D9/444; D9/689**

(58) Field of Classification Search D9/682-694, D9/516-575, 719, 434-436, 444, 445, 447-450, D9/455, 499; 222/129, 135, 153.01, 153.03, 222/153.04, 153.09, 153.11-153.14, 182, 222/631, 635, 209, 211-213, 215, 321.7-321.9, 222/372, 373, 378, 379, 383.1, 384-386, 222/398, 400.7, 400.8, 401, 402.1-402.25; 215/379-385; 220/669-675

Primary Examiner — Catherine Tuttle

(57) **CLAIM**

The ornamental design for a container shroud, as shown and described.

DESCRIPTION

FIG. 1 is an isometric view of the top, front and right side of the container shroud showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines are included for the purpose of illustrating portions of the container shroud that form no part of the claimed design.

1 Claim, 4 Drawing Sheets
